The ornamental design for a stand assembly, as shown and described.

DESCRIPTION

The present application is related to U.S. patent application Ser. No. 29/530,172 entitled “A Camera Assembly,” filed on Jun. 14, 2015; U.S. patent application Ser. No. 29/530,170 entitled “A Receiving Element of a Stand Assembly,” filed on Jun. 14, 2015; and U.S. patent application Ser. No. 29/530,169 entitled “A Base Assembly,” filed on Jun. 14, 2015, each of which is hereby incorporated by reference in its entirety.

FIG. 1 is a perspective view of a stand assembly showing the new design.

FIG. 2 is a side view of the stand assembly shown in FIG. 1.

FIG. 3 is a front view of the stand assembly shown in FIG. 1.

FIG. 4 is a top view of the stand assembly shown in FIG. 1. FIG. 5 shows a perspective view of a camera assembly that includes a camera module and the stand assembly showing the new design; and,

FIG. 6 shows a perspective view of another camera assembly that includes a camera module, a mount structure and the stand assembly showing the new design.

The broken lines depicting portions of a stand assembly in the above described figures form no part of the claimed design. The broken lines showing a camera in FIGS. 5 and 6, and the broken lines showing a fastener structure coupling a receiving element and a base of the stand assembly in FIGS. 1-3 and 5-6, and the broken lines showing a mounting
